COMBINED STAPLE REMOVER AND CARTON OPENING TOOL

Nathaniel M. Olney, New York, N.Y., assignor to Swing-line Inc., Long Island City, N.Y., a corporation of New York

Filed July 31, 1964, Ser. No. 81,102

Term of patent 14 years

(Cl. D74—1)

Des. 201,731

PAGE 2

FIG. 3

FIG. 4

FIG. 5

FIG. 5

FIG. 1 is a side elevational view of a combined staple remover and carton opening tool showing my new design.

FIG. 2 is a top plan view thereof.

FIG. 3 is a bottom plan view thereof.

FIG. 4 is a front view thereof.

FIG. 5 is another side elevational view of the combined staple remover and carton opening tool shown in FIG. 1 as it appears in closed position with the cutting blade in extended position.

FIG. 6 is an elevational view of the combined staple remover and carton opening tool as seen from the side opposite to that of FIG. 1.

I claim:

The ornamental design for a combined staple remover and carton opening tool, as shown.
